UNITED STATES PATENT OFFICE.

NILS FREDRIKSSON, OF STOCKHOLM, AND HERMAN ALFRED EDWARD HÄRSTEDT AND KARL GUSTAF LINDBERG, OF SVEDALA, SWEDEN, ASSIGNEES TO AKTIEBOLAGET ABJÖRN ANDERSON, OF SVEDALA, SWEDEN, A COMPANY OF SWEDEN.

ROOFING-TILE PRESS.

Application filed July 24, 1922. Serial No. 577,115.

To all whom it may concern:

Be it known that we, NILS FREDRIKSSON, HERMAN ALFRED EDWARD HÄRSTEDT, and KARL GUSTAF LINDBERG, subjects of the 5 King of Sweden, residing, respectively, in Stockholm, Sweden, Svedala, Sweden, and Svedala, Sweden, have invented a new and useful Improvement in Roofing-Tile Presses, of which the following is a specification.

The moulding of flanged roofing-tile is usually carried on in such manner that clay pieces, or so called blocks, of such size that each block is sufficient for the moulding of 15 one roofing-tile, are pressed between moulding members movable towards and away from one another, one of said members, the plunger or press head, being as a rule movable vertically against the other member, 20 the lower mould, which latter is capable of being turned, for the purpose of delivering the moulded tiles on a board or the like. The movement of the press head and mould is often effected by mechanical power in so 25 called roofing-tile presses, of which there are quite a number of constructions which operate more or less automatically. No such heretofore known construction, however, has proved to be quite satisfactory. 30 The most perfect presses are probably the so-called revolving presses in which a number—usually five—of lower moulds are secured to a prism having the same number of sides as the number of lower moulds, and 35 which prism is rotated step by step around its horizontal axis so that one lower mould after another is moved to pressing position below the press head which is movable up and down. Also such revolving presses, 40 however, have several serious disadvantages. The lower mould on which the clay body is to be placed, occupies at the moment when such positioning is to be effected, always a more or less inclined position owing to 45 which the clay body will not rest securely on the mould unless the workman who places the bodies, holds the body on the lower mould with his hand until during the subsequent rotation of the prism the lower 50 mould has reached approximately horizontal position. It will thus easily happen that the workman keeps his hand on the body a moment too long so that he gets his hand pinched. To avoid such accidents

more or less complete safety devices have 55 been provided, all of which, however, have entailed further disadvantages. Furthermore, it is a disadvantage that the lower mould from which the pressed roofing-tile shall be removed, does not occupy a position 60 suitable for such removal, and that while being at rest it is immovable which renders it impossible to shake the mould in order to facilitate the removal.

The present invention refers to a roofing-tile press which in respect of automatic operation is fully comparable to the revolving presses above described without possessing their disadvantages referred to. The new press which, in the well known manner 70 above referred to, is provided with a vertically movable press head which cooperates with a plurality of lower moulds arranged to be rotated in such manner that they may be moved one after another to pressing position below the press head, is chiefly characterized by this that all lower moulds are 75 rotatable in unison on a vertical shaft for the purpose of moving them in under the press head, and that each lower mould is 80 separately rotatable on a horizontal shaft for the purpose of emptying the lower moulds. In this manner the result is obtained that when placing the clay bodies upon the lower moulds said moulds may 85 always occupy a perfectly horizontal position so that it is unnecessary to hold the bodies by hand, and it will also be possible to shake the moulds for the purpose of facilitating the removal of the pressed tiles, the 90 moulds being free to be rotated when occupying the emptying position. On the other hand when the moulds are in the filling and pressing positions they should of course be maintained in horizontal position by 95 suitable guides.

In the accompanying drawings an embodiment of the invention is illustrated by way of example. Fig. 1 shows a side view of a roofing-tile press according to the invention, and Fig. 2 shows a front view of the press, and Fig. 3 a top plan view of the same the upper portions being omitted for rendering the drawing clearer. Fig. 4 is a plan view and Fig. 5 is an end view of the 100 guides for the lower moulds.

In the upper part of the press frame 1 a driving shaft 2 is journaled which sup-

ports at its one end two pulleys, one free pulley 3 and one driving pulley 4. A toothed pinion 5 is secured to the other end of the shaft 2 and meshes with a larger gear wheel 6 on a shaft 7 parallel with the shaft 2. A cam disk 8 is secured to the gear wheel 6 said cam disk effecting the turning of the lower moulds in a manner further described here below, and an eccentric disk 9 is secured to the shaft 7 and actuates a slide 10 slidable in the frame so that said slide moves up and down. The plunger or press head 11 is secured to the lower end of the slide 10.

15 The press illustrated in the drawings is provided with four lower moulds 12 each of which is rotatable on a horizontal shaft 13. The inner ends of said shaft are secured to a cross-shaped table 14 which is 20 rotatable around a vertical shaft 15 in the centre of the cross, said shaft being secured to the frame 1. Referring to Fig. 3 which shows the four lower moulds 12 viewed from above, A denotes the position for filling the 25 lower moulds, B the position for pressing—immediately below the press head which is not shown in this figure—C the position for trimming the moulded roofing-tiles, and D the position for emptying the lower 30 moulds. The table 14 with the four lower moulds is rotated step by step in the direction indicated by the arrow in Fig. 3, each time through an angle of 90°, so that one lower mould after another is turned to 35 the pressing position B below the press head. In order to effect said step by step rotation four pawls 16 are pivoted in recesses in the lower face of the table 14, said pawls co-operating with radial studs 17 on a drum 40 18 located below the table and rotatable on the shaft 15. A chain 19 is partly wound on the drum, one end of said chain being secured to the outside of the drum, and the other end of the chain being connected by 45 means of a rod 20 with one arm 21 of a bell crank lever pivoted on the stud 22 secured to the frame, the other arm 23 of said lever carrying a roller 24 which is actuated by the cam disk 8 above referred to. A strong 50 spiral spring, not shown in the drawing, is located in the drum 18, said spring turning the drum back a quarter of a rotation after each operation period and maintaining at the same time the roller 24 in engagement with the cam disk 8. The table 14 55 does not take part in this back-turning of the drum.

The lower moulds are normally maintained in the horizontal position shown in 60 Figs. 1-3 with the upper face directed upwards, partly by an arcuate guide rail 25 rigidly connected with the frame 1, and partly by a few shorter guide rails 26 on which the lower moulds rest during the 65 pressing so that the shafts 13 will not be

subjected to bending stresses during the pressing. As shown in Figs. 3 and 4, however, the guide rail 25 is cut off opposite the emptying position D, so that when the lower moulds occupy this position, they are 70 capable of turning on their shafts 13 and may thus be turned upside down for the purpose of being emptied, see Figs. 3 and 5. In order to facilitate the turning each lower mould is provided with a handle 27. The turning of the lower moulds is limited also in the emptying position D; however, by two lugs 28 and 29 the former of which is provided on the lower mould and the latter on the table 14 in such position 80 that the lug 28 on the lower mould will strike against the other lug when the lower mould has been turned upside down, that is to say half a rotation from the normal position. If the tile does not come loose 85 from the lower mould by merely said mould turning upside down, the mould may thus be turned slightly back and afterwards it may be given a slight shock by making the lug 28 on the mould strike against the lug 90 29 on the table. In this manner the roofing-tile will easily come loose from the lower mould and may be received in the ordinary manner on a board or other suitable support. Finally, there is secured to 95 each lower mould a roller 30 which, when the emptying is completed and the moulds are again put into motion from the emptying position B to the filling position A, will strike against an inclined surface 31 on 100 the end of the guide rail 25 and will thus automatically turn back the mould half a rotation so that when reaching the filling position A it will again occupy its normal position. 105

In order to limit the turning movement of the lower moulds in the correct positions so that the lower mould in which pressing is to take place, comes right below the press head, there is provided in the frame 1 a 110 counter-weighted arm 32 secured to an oscillatory shaft 33 on the end of which projecting outside the frame a crank pin 34 is secured. Said crank pin is actuated by two oppositely arranged lugs 35 and 36 on 115 the lever arm 21, Fig. 1, so that the locking arm is turned away downwards by the lug 36 when the arm 21 moves to the left in Fig. 1, and is afterwards again moved by the counter-weight and the lug 35 upwards 120 into the path of the outer end of the next shaft 13 when the arm 21 moves back to the right in Fig. 1 and turns the lower moulds.

In order to reduce the force necessary for 125 turning the table 14 with the lower moulds, the table is raised slightly—corresponding to the distance x in Fig. 2—before the turning is initiated, so that the moulds become free from and do not slide on the guide rail 130

25. Such raising of the moulds is effected simply by means of the inclined position of the pawls 16 shown in Fig. 2, said position being so chosen that at the initial turning 5 of the drum 18 in the direction indicated by the arrow in Fig. 2 when the studs 17 engage the lower ends of the pawls, the studs will first raise the table by the intermediary of the pawls, until the table comes to bear 10 against a collar 37 on the shaft 15, and afterwards the studs will turn the table. When the drum 18 is turned back, the table and the moulds are again lowered.

The operation of the press will be understood 15 from the above description and the drawing. The cam disk 8 and the eccentric disk 9 should of course be so set one relatively to the other that the turning of the table with the lower moulds takes place 20 while the press head 11 is raised. The proportioned clay bodies are placed on the lower moulds when in the position A, and in view of the fact that in this position as well as during the entire movement between A and B 25 the lower moulds occupy a horizontal position, it is not necessary to keep the clay bodies on the moulds with the hand. The pressing is effected in the position B, and in the position C the pressed roofing-tiles 30 are trimmed either by hand or automatically by means of a suitable cutter which may be rigidly connected with the slide 10 and move up and down simultaneously with the same. Finally, in the position D the lower moulds 35 are emptied which operation is essentially facilitated by the moulds being free to turn in this position, so that, if required, the tiles may be caused to come loose by a slight shaking of the moulds.

40. We claim:

1. In a roofing-tile press the combination of a vertically movable press head, and a plurality of lower moulds capable of turning in unison around a vertical axis so as to be 45 movable one after the other to pressing position below said press head, each of said lower moulds being separately capable of turning around a horizontal axis substantially radial and perpendicular to said first named axis.

2. In a roofing-tile press the combination of a vertically movable press head, a plurality of lower moulds capable of turning in unison around a vertical axis so as to be 55 movable one after the other to pressing position below said press head, each of said lower moulds being separately capable of turning around a horizontal axis substantially radial and perpendicular to said first named axis, and guides for said lower moulds stationary in relation to said moulds and located below said press head and extending so far to one side thereof substantially concentrically with said vertical axis that the 60 lower mould beneath said press head as well

as the next lower mould in the direction of rotation of said lower moulds are guided by said guides.

3. In a roofing-tile press the combination of a vertically movable press head, a plurality of lower moulds capable of turning in unison around a vertical axis so as to be movable one after the other to pressing position below said press head, each of said lower moulds being separately capable of turning around a horizontal axis, lugs on 70 said lower moulds, and lugs stationary in relation to said lower moulds and located in such manner that they may be struck by said first named lugs on said lower moulds 80 when rotated around their horizontal axes, for the purpose by such striking of said lugs against one another to facilitate the emptying of said lower moulds.

4. In a roofing-tile press the combination of a vertically movable press head, a plurality of lower moulds, a horizontal shaft for each of said lower moulds, a member carrying said horizontal shafts, a vertical shaft for said member located in such relation to said press head that said lower moulds are capable of turning in unison one after the other to pressing position below 90 said press head, driving means for producing a reciprocating vertical movement of 95 said press head, and means connected with said driving means for producing a step by step rotary motion of said member around said vertical shaft in a definite time relation to the vertical movements of said 100 press head.

5. In a roofing-tile press the combination of a vertically movable press head, a plurality of lower moulds, a horizontal shaft for each of said lower moulds, a member carrying said horizontal shafts, a vertical shaft for said member located in such relation to said press head that said lower moulds are capable of turning in unison one after the other to pressing position below 105 said press head, driving means for producing a reciprocating vertical movement of 110 said press head, pawls pivoted to said member, a drum located below said member and rotatable around said vertical shaft, studs on said drum adapted to be engaged by said pawls, and means connected with said driving means for producing a rotary motion of said drum around said vertical shaft.

6. In a roofing-tile press the combination of a vertically movable press head, a plurality of lower moulds, a horizontal shaft for each of said lower moulds, a member carrying said horizontal shafts, a vertical shaft for said member located in such relation to said press head that said lower moulds are capable of turning in unison one after the other to pressing position below 120 said press head, driving means for producing a reciprocating vertical movement of 125 said press head, and means connected with said driving means for producing a rotary motion of said drum around said vertical shaft.

said press head, pawls pivoted to said member, a drum located below said member and rotatable around said vertical shaft, studs on said drum adapted to be engaged by said pawls, means connected with said driving means for producing a rotary motion of said drum around said vertical shaft, and guides for said lower moulds located below said press head and extending so far to one side thereof that the lower mould beneath said press head as well as the next lower mould

15
in the direction of rotation of said lower moulds are guided by said guides, said pawls occupying such inclined position that at the initial turning of said drum caused by said means said member will be raised by the engagement of said pawls with said studs to such position that at the subsequent turning the lower moulds do not slide on said guides.

NILS FREDRIKSSON.

HERMAN ALFRED EDWARD HÄRSTEDT.

KARL GUSTAF LINDBERG.
